Primary Examiner — Kimberly Barnes(74) *Attorney, Agent, or Firm* — Michael Best & Friedrich LLP(57) **CLAIM**

We claim the ornamental design for a portable cleaner, as shown and described.

DESCRIPTION

FIG. 1 is a perspective view of a portable cleaner showing our new design.

FIG. 2 is a front side view of the portable cleaner of FIG. 1. FIG. 3 is a back side view of the portable cleaner of FIG. 1. FIG. 4 is a right side view of the portable cleaner of FIG. 1. FIG. 5 is a left side view of the portable cleaner of FIG. 1. FIG. 6 is a top side view of the portable cleaner of FIG. 1; and,

FIG. 7 is a bottom side view of the portable cleaner of FIG. 1.

The broken lines depict portions of the portable cleaner that form no part of the claimed design.
